(57) CLAIM

The ornamental design for a wine aerator, as shown and described.

DESCRIPTION

FIG. 1 is a perspective view of a wine aerator showing my new design;

FIG. 2 is a front view thereof;

FIG. 3 is a side view thereof;

FIG. 4 is a top plan view thereof; and,

FIG. 5 is a bottom plan view thereof.

The broken lines set forth in the several figures are for the purpose of illustrating unclaimed portions of the design and form no part of the claimed design.
